VENTILATING SASH FASTENER

Original Filed June 27, 1927

UNITED STATES PATENT OFFICE

RUDOLF KRASBERG, OF CHICAGO, ILLINOIS

VENTILATING-SASH FASTENER

Application filed June 27, 1927, Serial No. 201,670. Renewed April 3, 1929.

This invention has for its object to provide a simple, cheap and efficient sash-fastener of the type which permits of a partial opening of the window for ventilation purposes, a further object of the invention being to provide a device of this character which operates automatically to limit the relative opening movement of window sashes and requires manual manipulation to permit full opening of the same.

A further object of the invention is to provide a device of the character set forth the parts of which become interengaged as soon as one of the sashes is moved a distance substantially equal to that required to cause the lower edge of the lower rail of the lower sash to become flush with the top surface of the inner sill of the window.

Other objects of the invention will be readily understood from the following description.

The preferred embodiment of the invention is illustrated in the accompanying drawings wherein:

25 Figure 1 is a fragmentary view in elevation of a portion of a conventional slide-sash window, latching from within the building, equipped with a sash-fastener constructed in accordance with the invention.

30 Figure 2 is a fragmentary vertical section on the line 2—2 of Figure 1.

Figure 3 is a fragmentary plan section on the line 3—3 of Figure 2.

Figure 4 is a detail vertical section on the 35 line 4—4 of Figure 2.

The device comprises a bell crank lever 1 pivotally mounted at its elbow portion between the flanges 2 of the plate 3 which is mounted upon the top face of the upper rail 4 of the lower sash 5. One end portion of the lever 1 is of greater length and weight than the other end portion thereof and terminates in a projection 6 which normally (by gravity) projects over the upper face of the lower rail 7 of the upper sash 8, said lever being sufficiently loosely pivotally mounted to permit it to swing freely.

Pivotally secured at its upper end to the inner face of a side rail of the upper sash is a 50 sheet metal plate 9, the respective end por-

tions of which extend angularly of each other, said plate being of such length and its pivotal connection with the side rail of the upper sash so disposed that the lower end of said plate normally rests upon the upper face of the 55 lower rail 7 and, when so disposed, the lower end portion 10 of said plate 9 is vertically disposed. A continuous longitudinal slot 11 in said plate 9 follows the contour thereof in parallelism with the side edges thereof, said 60 slot terminating short of the terminals of said plate.

The position of the bell-crank lever 1 on the upper rail of the lower sash is such, with respect to the lower end portion of said plate 65 9, that the end portion of said lever carrying the projection 6 projects through the vertically disposed end portion of the slot 11 of the plate 9 when the sashes are in closed or substantially closed position and said plate 70 9 is in its normal position. The pivotal association of said plate 9 with the side rail of the upper sash must necessarily be also sufficiently loose to permit said plate 9 to be maintained by gravity in its normal position. 75

The several above-described elements being in relatively normal positions, it will be seen that upon raising the lower sash or lowering the upper sash a distance substantially equal to the depth of the shoulder provided by the 80 outer edge of the inner portion of the window sill, the projection 6 of the lever 1 will become disposed just above the vertical portion of the slot 11 and in engaging relation to the angularly disposed upper end portion of the plate 85 9 and thus the said lever 1 may not be moved out of such engaging relation without returning the sashes to approximately their relative closed positions. Further relative opening movement of said sashes will cause the lever 90 9 to contact with an inner side wall of the slot 11 and thus turn the plate 9 on its pivot until it becomes substantially inverted and the lever 9 engages the normally lower end wall of the slot 11 as shown in dotted lines 95 in Figure 1.

If, however, prior to effecting relative opening movement of the sashes, the lever 1 is moved to the position shown in dotted lines 100 in Figure 2, and is held in this position until

the projection 6 is disposed above the vertical portion of the slot 11, the sashes may be moved to full open position, the lever 1 being released after passing the point last above-mentioned. Upon restoring the sashes to closed position the lever 1 will be turned on its pivot to position to slide over the inner face of the portion of the plate 9 disposed in its path by said portion and will then 10 turn to the normal position shown in Figure 2. Consequently, unless the lever 1 is intentionally operated to permit full opening of the window the latter can be opened only to the limited extent indicated. Obviously 15 this limited opening is intended to permit ventilation and safeguard against burglary.

For low cost and ease of manufacture, the plate 3 consists of two equal portions each of which is provided with a flange 2, the latter being secured against separation and their 20 relative pivotal movement resisted by means of the rivet 12 having a middle portion 13 of greater diameter than the end portions thereof, said portion 13 being of somewhat 25 greater length than the thickness of the lever 1 of which it constitutes the pivot, the said portion 13 thus functioning as pivot and spacing element.

Preferably the side portions of the plate 3 are so formed that they present straight edge 30 portions 14 inwardly of their extreme inner and outer edge portions, the latter being preferably disposed to overlap the upper face of the lower rail of the upper sash in order to 35 prevent manipulation of the lever 1 by inserting a knife blade or the like through the space between the opposing faces of the meeting rails of the sashes from the exterior of the building and, to this end, the two parts of 40 the plate 3 adjacent the flanges 2 are provided with contacting meeting edges to prevent manipulation of the lever 1 by insertion of a wire in place of the knife blade or the like. The edge portions 14 opposing the upper 45 sash constitute gauges to guide the person securing the plate 3 in properly positioning the latter on the lower sash with respect to the inner or meeting edge of its upper or meeting rail.

50 I claim as my invention:

1. A device of the kind specified comprising a longitudinally slotted member having a bend between its ends pivotally secured at its upper end to a side rail of the upper sash 55 of a window, for normally positioning by gravity with the lower end portion of the slot therein vertically disposed, a lever loosely pivotally mounted upon the lower 60 sash for normal positioning with one end thereof projecting through said vertical portion of said slot when the sashes are in closed position, and a projection at the inner end of said lever adapted to engage a portion of 65 said member as said lever moves toward the end of said portion of said slot during initial

relative opening movement of the window sashes.

2. A device of the kind specified comprising a member pivotally secured to a side rail of the upper sash of a window and provided with a continuous longitudinal slot, one part of which extends angularly of the other part thereof, one of said parts being vertically disposed when said member is in normal position and the other then extending at an upward incline, a lever pivotally mounted on the lower sash and having one end portion normally projecting through the vertically disposed portion of said slot when the sashes are in substantially closed position, said end portion of said lever provided with a projection adapted to engage a portion of said member bordering the upwardly inclined portion of said slot as the sashes are moved to partially open position to thereby prevent disengagement of said lever with said member. 70 75 80 85

3. A device of the kind specified comprising a member pivotally secured to a side rail of the upper sash of a window and provided with a continuous longitudinal slot, one part of which extends angularly of the other part thereof, one of said parts being vertically disposed when said member is in normal position and the other then extending at an upward incline, a lever pivotally mounted on the lower sash and having one end portion normally projecting through the vertically disposed portion of said slot when the sashes are in substantially closed position, said end portion of said lever provided with a projection adapted to engage a portion of said member bordering the upwardly inclined portion of said slot as the sashes are moved to partially open position to thereby prevent disengagement of said lever with said member, the latter and said lever arranged to maintain their interengagement with each other during closure thereof to thereby effect self-restoring of said member to normal position during such closure. 90 95 100 105 110

4. A device of the kind specified comprising a member pivotally secured to a side rail of the upper sash of a window and provided with a continuous longitudinal slot, one part of which extends angularly of the other part thereof, one of said parts being vertically disposed when said member is in normal position and the other then extending at an upward incline, a device mounted on the lower sash and having one end portion normally projecting through the vertically disposed portion of said slot when the sashes are in substantially closed position, said end portion of said device provided with a projection adapted to engage a portion of said member bordering the upwardly inclined portion of said slot as the sashes are moved to partially open position to thereby prevent disengagement of said device with said mem- 115 120 125 130

ber, said device being manually operable to maintain the same out of engaging relation to said member to permit full relative opening movement of the sashes.

5. A device of the kind specified comprising a member pivotally secured to a side rail of the upper sash of a window and provided with a continuous longitudinal slot, one part of which extends angularly of the other part thereof, one of said parts being vertically disposed when said member is in normal position and the other then extending at an upward incline, a manually shiftable device mounted on the lower sash and having one 15 end portion normally projecting through the vertically disposed portion of said slot when the sashes are in substantially closed position, said end portion of said device provided with a projection adapted to engage a portion of said member bordering the upwardly inclined portion of said slot as the sashes are moved to partially open position to thereby prevent disengagement of said device with said member, said device being manually operable to maintain the same out of engaging 20 relation to said member to permit full relative opening movement of the sashes, said member and said device remaining interengaged during closing movement of said 25 sashes to thereby restore said member to its normal position.

6. A device of the kind specified including a bell crank lever, and a pivotal support therefor comprising a pair of equal plates 35 having opposed meeting edges, a flange spaced from the meeting edge of each plate to provide space between said flanges for the reception of said lever, and a pivot member for the latter secured at its ends to the respective flanges for coupling said plates.

40 7. A device of the kind specified including a bell crank lever, and a pivotal support therefor comprising a pair of equal plates having opposed meeting edges, a flange 45 spaced from the meeting edge of each plate to provide space between said flanges for the reception of said lever, and a pivot member having a middle portion of greater diameter than its end portions and constituting a spacing member for determining the spacing of 50 said flanges from each other independently of said meeting edges, the end portions of said pivot member secured to said flanges and said middle portion thereof constituting the 55 pivot for said lever.

8. A device of the kind specified including a bell crank lever, and a pivotal support therefor comprising a pair of equal plates having opposed meeting edges, a flange 60 spaced from the meeting edge of each plate to provide space between said flanges for the reception of said lever, and a pivot member having a middle portion of greater diameter than its end portions and constituting a spacing member for determining the spacing of 65

said flanges from each other independently of said meeting edges, the end portions of said pivot member secured to said flanges and said middle portion thereof constituting the pivot for said lever, said plates having edge portions extending perpendicularly to the planes of said flanges and disposed inwardly of their extremes, said edge portions constituting gauges for cooperation with the meeting edge of the meeting rail of the lower sash of a 70 window for positioning said plates on the said rail.
